UNITED STATES PATENT OFFICE.

GEORGE A. CAGE, OF MINEOLA, TEXAS.

CAR-CO尤LING.

SPECIFICATION forming part of Letters Patent No. 279,332, dated June 12, 1883.

Application filed October 30, 1882. (No model.)

To all whom it may concern:

Be it known that I, GEORGE A. CAGE, a citizen of the United States, residing at Mineola, in the county of Wood and State of Texas, have invented certain new and useful Improvements in Car-Coupling Devices, of which the following is a specification, reference being had therein to the accompanying drawings.

My invention relates to car-couplers, the object being to provide a coupler with a coupling-pin of improved construction, and to combine said pin with effective and durable devices for raising and lowering it.

The invention consists in the combinations of parts hereinafter fully described, and pointed out in the claim.

In the drawings, Figure 1 is a perspective view of a coupler provided with my improvement. Fig. 2 is a vertical longitudinal section thereof, and Fig. 3 represents the coupling-link detached.

A represents a portion of an end of a car, and B is the draw-head, provided with an extension, C, the latter being longitudinally grooved to receive a spring, D, and an extension of a sliding block, E, the latter being adapted to enter the draw-head. The spring D bears against the block.

F represents a vertical rod supported in guides f on the end of the car, and having a looped right-angular arm, F'.

G represents a lever pivoted at one end to the end of the car, and formed with a loop, g, to surround the arm F', and terminating in a handle, g'.

H represents a coupling-pin provided with a loop, g'. This loop is adapted to be inserted through the looped end of the arm F' of the rod F, and secured by a cross-pin, h, or other equivalent means. The pin H passes 40 through an opening in the draw-head, and is adapted to fall into the link when the block E is forced back by the thrust of the link.

I represents the coupling-link, formed with square ends, i, to adapt it to squarely strike 45 the block E.

The pin H may be readily removed when desired, and is capable of slight movement in the loop of the arm F'.

Having fully described my invention, what I claim as new, and desire to secure by Letters Patent, is—

The combination, with a vertical rod secured by keepers to the end of a car, and provided with a looped end, F', of a coupling-pin having a loop at its upper end adapted to project through the loop of the arm F' and be retained by a cross-pin, and a lever pivoted at one end to the end of the car and looped to surround the arm F', and terminating in a 60 handle, substantially as set forth.

In testimony whereof I affix my signature in presence of two witnesses.

GEORGE A. CAGE.
